RESTORING MECHANISM FOR CALCULATORS.

1,232,018.

Specification of Letters Patent.

Patented July 3, 1917.

Application filed June 1, 1916. Serial No. 101,019.

To all whom it may concern:

Be it known that we, WARREN FUHRMANN, a citizen of the United States, and a resident of Westfield, county of Union, 5 and State of New Jersey, and EDWARD M. SQUAREY, a subject of the King of Great Britain, and a resident of Tuckahoe, county of Westchester, State of New York, have invented certain new and useful Improvements 10 in Restoring Mechanism for Calculators, of which the following is a specification.

One of the objects of the present invention is to provide in a calculator including 15 transfer mechanism, improved means for actuating the restoring member, whereby it will be moved to cause both the restoring and the transfer to take place during the return movement of a side bar or main actuating member of the machine.

Another object of the invention is to provide means for actuating the restoring bar of a transfer mechanism from an actuating member that moves back and forth; and 25 means for moving the adding pinions relative to the rack bars to engage and disengage the same, which latter means include a member that upon special operation of the machine to change the normal timing 30 of the said engagement and disengagement of the pinions, will disable the connections for shifting the restoring bar.

In the accompanying drawings illustrating one embodiment of our invention, Figure 1 is a side elevation at the left side of the machine. Fig. 2 is a fragmentary view of similar parts on the right side of the machine. Fig. 3 is a view similar to Fig. 1, with the parts shown at the end of the 40 advance stroke of the pitman. Fig. 4 is a partial plan view; Figs. 5, 6, and 7 show the parts on one side of the machine in different consecutive positions. Fig. 8 shows one of the latches; and Fig. 9 shows one of the pawls.

As shown in the drawings, 20 represents the side plate on the right side of an adding machine, and in Fig. 2 is shown a portion 21 of a similar side plate on the opposite 50 side of the machine. These plates are provided with guiding means for a restoring bar 22 that extends across between the plates and beyond them, and is secured at its ends to links 23 and 24 that extend horizontally

adjacent each side plate respectively. Slots 55 25 and 26 are shown in the two side plates through which the bar 22 extends and is guided therein to move back and forth. Suitable means are provided to move the arms 23 and 24 back and forth in unison, 60 and the means shown are in duplicate, on each of the side plates. The link 23 is pivoted to an arm 27 that swings on a stud 28 on the side plate 20, which arm is hinged at 19 to one arm 30 of a bent lever, that 65 swings on a stud 29 on this side plate. The depending arm 31 of the bent lever extends downwardly and carries a latch 32 pivoted thereon at stud 33. This latch has a lug portion 34, the front part of which is inclined, and beyond the lug the latch in its normal position rests on a stud 35, carried by an arm 36 secured to the pitman 37, on this side of the machine. This pitman is advanced and retracted by a crank 38 from 70 an actuating shaft 39, in the operation of the machine. At the rear the pitman is shown as swung on a crank 40 on a shaft 41. A spring 42 between the latch and its lever presses the latch against the pin 35. 80

When the pitman 37 moves forward from the position shown in Fig. 1, to that shown in Fig. 3, the pin 35 will strike the inclined face of the lug and swing the latch upward, until it passes the lug 34, when the latch 85 will fall and the lug engage the pin, as indicated in Fig. 5.

On the opposite side of the machine, (see Fig. 2) the link 24 is hinged to an arm 43 that swings on a stud 44 on the side plate 90 21. This arm is pivoted to a bent lever comprising arms 45 and 46, that swings on a stud 47. A latch 48 is pivoted on the arm 46, and pressed downward by a spring 49 against a stud 50 on a strip 51, fast on a 95 pitman 52. This pitman, by means not shown, is swung from the shafts 39 and 41 to move back and forth in unison with the pitman 37. The latch 48 has a lug 53 inclined at its forward end, and which will 100 engage the stud 50 when the pitman 52 moves forward the full distance similar to the position of the latch and stud shown in Fig. 5. It is to be understood that the parts shown in Fig. 2 are substantial duplicates 105 of corresponding parts shown in Fig. 1.

As set forth, the forward movement of the two pitmen will cause the latches to

swing upward and permit the studs carried by the pitmen to engage the lugs on the latches. (See Fig. 3). When the pitmen begin the return stroke, each stud will engage its latch to draw it rearward, and the latch will move its supporting arm to swing each bent lever. This will cause the horizontal arm of each bent lever to swing upward, that will rock the arms 27 and 43 upward, and serve to straighten the toggle joints formed by these arms with the links 23 and 24. This will cause the two links to move forward in unison, that will shift the restoring bar 22 forward in the slots in the side plates as indicated in Fig. 6, in which position the pitmen have advanced a sufficient distance to operate the parts as shown. This is effected at the initial part of the return stroke of the pitman.

20 The purpose of the restoring bar is to control carrying segments 54, that coöperate with the adding pinions 55. These pinions are shifted back and forth between a position engaging the segments 54 as shown in Fig. 1, and a position engaging the rack bars 56, as shown in Figs. 3-7, by suitable means not herein shown. In the normal operation of adding, the pinions remain forward engaging the segments during the forward stroke of the pitman, and at the end of such stroke the pinions are shifted free of the segments and engage the rack bars. The pinions remain in such position until the latter portion of the return stroke, when they are brought forward to again engage the carrying segments. Therefore the carrying operation of the segments is effected at this latter part of the return stroke, when the pinions are again brought to engage the segments, and this is usually done by a spring 57 on each segment, by reason of the restoring bar moving rearward at this time to permit such spring to swing the segments. Those segments that have been tripped to carry, remain in this position at the end of an operation, and such segments are returned to a latched position when the restoring bar is moved forward at the initial part of the return stroke of the pitmen.

50 It is customary in this art, when the segments are restored, that they are engaged by a suitable latch or pawl, that is tripped when the pinion passes 9 to carry.

Therefore the restoring bar must be shifted to the position of Fig. 6 at the initial part of the return stroke of the pitmen. But since the pitmen continue their return stroke, the latches must be disconnected therefrom; and furthermore the restoring bar must be held in this position until the final portion of the return stroke and then released. Upon the latches being released from the pitmen studs, springs 58 and 59 connected with the links 23 and 24 respectively, will retract the restoring bar and the

connected parts at each side from the position of Fig. 6 to that of Fig. 1, when the parts are free to move. When the pitman advances the parts to shift the restoring bar the required distance, each latch is 70 swung to release its bent lever from the pitmen. Pins 60 and 61 on the two side plates are engaged by arms 62 and 63 on the latches at this stage, whereby latches are swung upward to move their lugs away 75 from the pins 35 and 50 carried by the pitmen. This freeing of the parts would permit the springs 58 and 59 to retract the links and restoring bar, so that suitable restraining means must be employed to prevent such movement at this time. The arm 31 at this stage is engaged by a shoulder 64 on a pawl 65 pivoted at 66, and pressed upward against the end of the arm by a spring 67; (see Fig. 6). On the other side, the 80 arm 46 engages a shoulder 68 on a pawl 69 pivoted at 70 on side plate 21, the pawl being pressed upward by a spring 71. These pawls will engage the arms just previous to the release of the latches from the pitmen studs, and hence hold the parts with the restoring bar in the forward position. This advance of the restoring bar by the latches and pitmen effects the restoring movement of the segments 54. 95

At the latter part of the return stroke of the pitmen, the pawls are shifted to release the arms 31 and 46 and permit the springs 58 and 59 to retract the restoring bar and connected parts. A pin 72 carried by pitman 37, at this stage will strike an arm 73 of the pawl 65, and shift the pawl to release the arm 31. On the opposite side a pin 74 on the pitman 52, will strike an arm 75 on the pawl 69, to shift this pawl and release 100 the arm 46, simultaneous with the release of the arm 31 from pawl 65. This will permit the return of the restoring bar and connected parts to former position as shown in Fig. 1. It will be understood that as soon as each pitman starts forward the pawls will be released from the pins on the pitmen to coöperate with the arms, as set forth. 110

It is also desirable to permit the restoring bar when moved forward the full distance 115 by the latches, to be held in a forward position for an instant, and then to be retracted a very slight distance, to be held in such retracted position until the release at the final part of the return stroke. The 120 pawl 65 is provided with a second shoulder 76 a short distance back of the shoulder 64; and the pawl 69 has a second shoulder 77 adjacent the shoulder 68 thereon. Upon release of the latches from their studs, a very 125 slight retraction of the pitman will bring cams 78 and 79 on the pawl arms 73 and 75 to engage the pins 72 and 74 respectively, whereby each pawl is given a short swing just sufficient to cause the arms 31 and 46 130

to be released by the shoulders 64 and 68, and to engage the shoulders 76 and 77; (see Fig. 7). It will be understood that these shoulders are a short distance offset, that will permit the slight retraction of the arms and hence of the restoring bar.

5 In machines of this character, special operations are effected, that are brought about by depression of special keys, that change 10 the timing of the engagement of the pinions with the rack bars and the segments. During such special operations no carrying is effected, and hence the restoring bar should not be shifted. We provide means whereby 15 during the depression of any of these special keys the mechanism for shifting the restoring bar is disabled. In Figs. 1 and 3 are shown special keys 80 and 81, that when either is depressed, will engage the lever 82 and depress the lever and hold it depressed 20 until the keys are restored. This lever is fast to a shaft 83 and will raise an arm 84 that is arranged to engage a pin 85 on the latch 33. This movement is sufficient to hold 25 the latch with its lug out of position for engagement with the stud 35 on the pitman. Therefore the latch will not be engaged by the advance of the pitman. The shaft 83 extends across the machine and carries an 30 arm 86 that serves to elevate a strip 87, (see Fig. 2). The latter will engage a pin 88 on the latch 48, so that this latch will be raised at the same time that the latch 32 is raised. Thus the depression of either key 35 will raise both latches and prevent any movement of the restoring bar by the pitmen, until the key is restored. Means are shown in Fig. 1 for retaining the keys 80 and 81 depressed when they are operated until the 40 return stroke of the pitman 37. A bar 2 is suitably guided to reciprocate and has inclined slots 3 and 4 that engage pins 5 and 6 on the keys 80 and 81 respectively. When either key is depressed the pin will engage 45 the wall of the slot and move the bar 2 rearward to further tension its retracting spring 7. The bar 2 is locked in its rearward position by a latch 8 that engages a notch 9 in the bar. The latch 8 carries a 50 pawl 10 that will be engaged by a pin 11 on the pitman 37 at the latter portion of its return stroke, whereby the latch will be swung to release the bar 2 and permit the keys 80 and 81 to be retracted by their springs 13 and 14. On the forward stroke the pawl 10 will swing and not shift the latch.

Having thus described our invention, what we claim is:—

1. The combination of a restoring bar, a 60 swinging lever, connections between the bar and lever, means to retract the bar and lever, a pitman, connections between the pitman and said lever comprising a latch pivoted on one of these members and a stop on 65 the other member arranged to be engaged by

the latch, the stop and latch being arranged whereby on the advance of the pitman the latch will shift without moving the lever, but on the return stroke of the pitman the latch will be engaged by the stop whereby to 70 swing the lever and shift the restoring bar, means arranged to engage the latch after its initial movement of the restoring bar, whereby the latch is released from the said stop, means arranged to engage said lever 75 when advanced by said means whereby to hold the lever and restoring bar in advanced position on release of the latch from the said stop, said means at the final part of the return stroke of the pitman being caused to 80 release said lever and permit full retraction of the lever and restoring bar.

2. The combination of a restoring bar, a swinging lever, connections between the bar and lever, means to retract the bar and lever, 85 a pitman, connections between the pitman and said lever comprising a latch pivoted on one of these members and a stop on the other member arranged to be engaged by the latch, the stop and latch being arranged whereby 90 on the advance of the pitman the latch will shift without moving the lever, but on the return stroke of the pitman the latch will be engaged by the stop whereby to swing the lever and shift the restoring bar, means ar- 95 ranged to engage the latch after its initial movement of the restoring bar, whereby the latch is released from the said stop, means arranged to engage said lever when advanced by said means whereby to hold the 100 lever and restoring bar in advanced position on release of the latch from the said stop, said means at the final part of the return stroke of the pitman being caused to release said lever and permit full retraction of the 105 lever and restoring bar, special keys on the machine, and means for causing the operation of said keys to shift the latch out of range of the said stop.

3. The combination of a restoring bar, a 110 swinging lever, connections between the bar and lever, means to retract the bar and lever, a pitman, connections between the pitman and said lever comprising a latch pivoted on one of these members and a stop on 115 the other member arranged to be engaged by the latch, the stop and latch being arranged whereby on the advance of the pitman the latch will shift without moving the lever, but on the return stroke of the pitman 120 the latch will be engaged by the stop whereby to swing the lever and shift the restoring bar, means arranged to engage the latch after its initial movement of the restoring bar, whereby the latch is released from the 125 said stop, means arranged to engage said lever when advanced by said means whereby to hold the lever and restoring bar in advanced position on release of the latch from the said stop, said means at the final part of 130

the return stroke of the pitman being caused to release said lever and permit full retraction of the lever and restoring bar, special keys on the machine, means for holding the keys down when depressed until the latter part of the return stroke of the pitman, and means for causing the depressed keys to hold each said latch out of range of engagement with its said stop.

4. The combination of a restoring bar, a swinging lever, connections between the bar and lever, means to retract the bar and said lever, a pitman, connections between the pitman and lever comprising a latch pivoted on one of these members and a stop on the other member arranged to be engaged by the latch, the stop and latch being arranged whereby on the advance of the pitman the latch will shift without moving the lever, but on the return stroke of the pitman the latch will be engaged by the stop whereby to swing the lever and shift the restoring bar, means arranged to engage the latch after its movement by the restoring bar whereby the latch is released from the pitman stop, means arranged to engage said lever when advanced by said means whereby to hold the lever and restoring bar in advanced position on release of the latch from the said stop, said means being arranged to shift after a short dwell of the lever whereby to hold the lever with the restoring bar retracted a short distance, and said means at the final part of the return stroke of the pitman being caused to release said lever and permit full retraction of the lever and restoring bar.

5. In a calculating machine, the combination with adding mechanism including a series of counters, of a restoring bar extending across the machine to coöperate with all of the counters, and a pitman on each side of the machine, of a lever swinging on each side plate, connections between each said lever and the bar, means on each side plate to retract the bar and lever, connections between each pitman and adjacent lever comprising a latch pivoted on one of these members and a stop on the other member arranged to be engaged by the latch, each stop and latch being arranged whereby on the advance of the pitman the latch will shift without moving the lever, but on the return stroke of the pitman the latch will be engaged by the stop whereby to swing the lever and shift the restoring bar, means arranged to engage each latch after its movement by the restoring bar whereby each latch is swung to be released by its said stop, means arranged to engage each lever upon the lever being advanced by the latch to hold the lever in advanced position on said release of the latch from the stop, said means at the final part of the return stroke of the pitman being caused to release said lever and permit full retraction of the lever and restoring bar by said means.

levers and permit retraction of the restoring bar.

6. In a calculating machine, the combination with adding mechanism including a series of counters, a restoring bar extending across the machine to coöperate with all of the counters, and a pitman on each side-plate of the machine, of a lever swinging on each side plate, connections between each said lever and the bar, means on each side plate to retract the bar and lever, connections between each pitman and adjacent lever comprising a latch pivoted on one of these members and a stop on the other member arranged to be engaged by the latch, each stop and latch being arranged whereby to swing the levers and shift the restoring bar, means arranged to engage each latch after its movement by the restoring bar whereby each latch is swung to be released by its said stop, means arranged to engage each lever upon the lever being advanced by the latch to hold the lever in advanced position on said release of the latch from the stop, said means at the final part of the return stroke of the pitman being caused to release said levers and permit retraction of the restoring bar, special keys on the machine, means for holding the keys down when depressed until the latter part of the return stroke of the pitman, and means for causing the depressed keys to hold each said latch out of range of engagement with its said stop.

7. The combination of a restoring bar, a swinging lever, connections between the bar and lever, means to retract the bar and lever, a pitman, connections between the pitman and said lever comprising a latch pivoted on one of these members and a stop on the other member arranged to be engaged by the latch, the stop and latch being arranged whereby on the advance of the pitman the latch will shift without moving the lever, but on the return stroke of the pitman the latch will be engaged by the stop whereby to swing the lever and shift the restoring bar, a pawl having a shoulder arranged to engage said lever when advanced by said means whereby to hold the lever and restoring bar in advanced position on release of the latch from the stop, a second shoulder on the pawl, means on the pitman to shift the pawl after a short dwell of the lever on the first shoulder to permit the second shoulder to engage the lever whereby to hold the lever with the restoring bar retracted a short distance by said means, and means on the pitman to swing the pawl at the final part of the return stroke of the pitman to release said lever and permit full retraction of the lever and restoring bar by said means.

- from the pitman, and means to swing each said pawl on the final part of the return stroke of the pitman to release said levers and permit retraction of the restoring bar 5 by said means, special keys on the machine, means for holding the keys down when depressed until the latter part of the return stroke of the pitman, and means for causing the depressed keys to hold each said latch out 10 of range of engagement with its said stop.
13. The combination of a restoring bar, a swinging lever, connections between the bar and lever, means to retract the bar and lever, a latch pivoted on said lever, a pit- 15 man, a stop on the pitman arranged to engage said latch, the stop and latch being arranged whereby on the advance of the pitman the latch will shift without moving the lever but on the return stroke of the pit- 20 man the latch will be engaged by the stop to swing the lever and shift the restoring bar, a fixed pin arranged to engage the latch after its initial movement by the pit- 25 man whereby the latch is swung on its lever to be released from the pitman stop, a pawl having a shoulder arranged to engage said lever when advanced by said means whereby to hold the lever and restoring bar in advanced position on release of the latch 30 from the pitman, a second shoulder on the pawl, means on the pitman to shift the pawl after a short dwell of the lever on the first shoulder to permit the second shoul- 35 der to engage the lever whereby to hold the lever with the restoring bar retracted a short distance by said means, and means on the pitman to swing the pawl at the final part of the return stroke of the pitman to release said lever and permit full retraction of the lever and restoring bar by said means. 40
14. In a calculating machine, the combination with adding mechanism including a series of counters, a restoring bar extending across the machine to coöperate with all of the counters, and a pitman on each side plate of the machine, of a lever swing- 45 ing on each side plate, connections between each lever and the bar, means on each side plate to retract the bar and lever, a latch pivoted on each said lever, a stop on each pitman arranged to engage with the adjacent latch, each stop and latch being arranged whereby on the advance of the pit- 50 man the latch will shift without moving the lever, but on the return stroke of the pitman the latch will be engaged by the stop to swing the levers and shift the restoring bar, a fixed pin on each side plate ar- 55 ranged to engage the adjacent latch after its initial movement by the pitman whereby each latch is swung on its lever to be re- 60 leased by its pitman stop, a pawl on each side plate having a shoulder arranged to engage the adjacent lever when advanced by said means whereby to hold the lever 65

and restoring bar in advanced position on release of the latches from the pitmen, a second shoulder on each said pawl, means to shift each pawl after a short dwell of the lever on the first shoulder to permit the second shoulder to engage the lever whereby to hold the lever with the restoring bar re- 70 tracted a short distance by said means, and means on the pitmen to swing each pawl at the final part of the return stroke of the pitmen to release said levers and permit full retraction of the levers and restoring bar by said means. 75

15. In a calculator, a combination of a restoring bar, shifting means for the bar, re- 80 tracting means for the bar and shifting means, a pitman, connections between the pitman and a member of the shifting means comprising a latch pivoted on one of these members and a stop on the other member engaged by the latch, the stop and latch being arranged whereby on advance of the pitman the latch will swing without moving the shifting means and bar but on the return stroke of the pitman the stop and latch will engage whereby to shift the restoring bar, means arranged to engage the latch after its initial movement by the restoring bar whereby the latch is moved to release said stop, means arranged to engage 85 and hold the shifting means and restoring bar in advanced position after slight re- triction on said release of the latch and stop, said holding means at the final part of the return stroke of the pitman being caused to release said shifting means to permit full re- 90 triction of the shifting means and restoring bar. 95

16. In a calculator, the combination with adding mechanism including a series of counters, a restoring bar extending across the machine to coöperate with all of the counters and a pitman on each side of the machine, of shifting means for the bar on each side plate of the machine, restoring 105 means for each said shifting means and the bar, connections on each side plate between the pitman and a member of the shifting means comprising a latch pivoted on one of these members and a stop on the other mem- 110 ber that is engaged by the latch, the stop and latch being arranged whereby on advance of the pitman each latch will swing without moving its shifting means and the bar but on return stroke of the pitman, each stop and latch will engage whereby to shift the restoring bar, means arranged to engage each latch after its movement by the restoring bar whereby the latch is swung to be released from its stop for retraction, 115 means on each side arranged to engage and hold each shifting means and the restoring bar in advanced position after slight re- triction on said release of each latch and stop, said holding means at the final part 120 125 130

- of the return stroke of the pitman being caused to release said shifting means to permit full retraction of the shifting means and restoring bar.
- 5 17. In a calculator, a combination of a restoring bar, shifting means for the bar, retracting means for the bar and shifting means, a pitman, connections between the pitman and a member of the shifting means comprising latch pivoted on one of these members and a stop on the other member engaged by the latch, the stop and latch being arranged whereby on advance of the pitman the latch will swing without moving 10 the shifting means and bar but on the return stroke of the pitman the stop and latch will engage whereby to shift the restoring bar, means arranged to engage the latch after its initial movement by the restoring bar 15 whereby the latch is moved to release said stop, means arranged to engage and hold the shifting means and restoring bar in advanced position on said release of the latch and stop, said holding means at the final 20 25 part of the return stroke of the pitman being caused to release said shifting means to permit full retraction of the shifting means and restoring bar.
18. In a calculator, the combination with adding mechanism including a series of
- counters, a restoring bar extending across the machine to coöperate with all of the counters and a pitman on each side of the machine, of shifting means for the bar on each side plate of the machine, restoring means for each said shifting means and the bar, connections on each side plate between the pitman and a member of the shifting means comprising a latch pivoted on one of these members and a stop on the other member that is engaged by the latch, the stop and latch being arranged whereby on advance of the pitman each latch will swing without moving its shifting means and the bar but on return stroke of the pitman, each stop and latch will engage whereby to shift the restoring bar, means arranged to engage each latch after its movement by the restoring bar whereby the latch is swung to be released from its stop for retraction, means on each side arranged to engage and hold each shifting means and the restoring bar in advanced position on said release of each latch and stop, said holding means at the final part of the return stroke of the pitman being caused to release said shifting means to permit full retraction of the shifting means and restoring bar.

WARREN FUHRMANN.
